UNITED STATES PATENT OFFICE.

FRIEDRICH W. MEYER, OF PITTSBURGH, PENNSYLVANIA, ASSIGNOR TO WESTING-HOUSE ELECTRIC AND MANUFACTURING COMPANY, A CORPORATION OF PENNSYLVANIA.

INVERTED RECTIFIER.

1,381,324.

Specification of Letters Patent. Patented June 14, 1921.

Application filed June 20, 1914. Serial No. 846,365.

To all whom it may concern:

Be it known that I, FRIEDRICH W. MEYER, a subject of the Emperor of Germany, and a resident of Pittsburgh, in the county of Allegheny and State of Pennsylvania, have invented a new and useful Improvement in Inverted Rectifiers, of which the following is a specification.

My invention relates to devices for transforming direct current into alternating current, and more particularly to devices of the character specified wherein the current is carried at the point of transition by means of a gas or vapor arc.

The object of my invention is to provide a device of the character specified which will be simple and effective in operation, which will have few moving mechanical parts, and which will require a minimum of attention.

It has previously been suggested in the United States patent to Kruh, No. 787,192, April 11, 1905, and Steinmetz, No. 787,228, April 11, 1905, to make use of the property of a vapor arc to seek a cool anode to provide apparatus for converting direct current into alternating current. The devices of these two patents depend entirely for their action upon this thermo effect, which is uncertain and erratic in its action, and which is affected to a marked extent when the entire device heats up with use and as the room temperature changes. Furthermore, changes in the load, with consequent changes in the strength and heating effect of the arcs, alter the frequency and operation of these devices to a marked extent. While they work successfully under ideal conditions in the laboratory, they are not susceptible of general commercial use because of these defects. It has furthermore been proposed to transform direct current into alternating current by means of a magnetically controlled vapor arc, in United States patent to Weintraub, No. 877,026.

January 21, 1908. The device of this patent operates by alternately blowing out or extinguishing the arc and has been found defective for the following reason. The only electrode material which has been found suitable for power-carrying arcs of this character, is mercury or compounds thereof or hydrogen or helium when using a Wehnelt cathode. The current-carrying parti-

cles in a mercury vapor arc are of considerable mass and hence possessed of considerable inertia, and when it is attempted to reverse the direction of movement of an arc of this character, at a reasonably high rate, such, for example, as that which is attendant upon commercial frequencies, an unnecessarily large number of ampere turns must be employed to provide a very powerful controlling field before effective operation is assured. It is a well-known fact that much less energy is required to move a heavy mass alternately from one point to another by causing it to revolve in a circular path which includes both of said points, rather than in causing it to reciprocate, because the sudden stoppage of a moving mass is invariably attended by a loss of energy. I avail myself of this phenomenon to provide a de-rectifying device somewhat similar to that of Weintraub, but in which the arc-bearing material, possessing considerable inherent mass, is forced to travel in a circular path and hence smooth operation is assured.

Not only may energy in the form of an electromagnetic field be employed for controlling the arc, but I have found that energy in the form of an electrostatic field also furnishes a very effective control, and I make use of either of these methods of control or of a system wherein both are combined.

Referring to the accompanying figures, Figure 1 is a side view, partially in section and partially in elevation, of a multi-current, multi-frequency inverted rectifier constructed in accordance with my invention. Fig. 2 is a bottom view, in plan, of the device shown in Fig. 1. Figs. 3 and 4 are perspective views illustrating the de-rectifying action of an arc in the device of Figs. 1 and 2. Fig. 5 is a side view, partially in section and partially in elevation, of an inverted rectifier, wherein the arc is actuated in a circular manner by means of a combined electrostatic and electromagnetic field, the tubes of force of each field being parallel to those of the other. Fig. 6 is a top plan view of the device of Fig. 5. Fig. 7 is a bottom plan view thereof. Fig. 8 is a plan view of a modification of the device shown in Figs. 1 and 2. Fig. 9 is a side view, in section, of the device shown in Fig.

8, and Fig. 10 shows a modified form of rotating energy field wherein both electrostatic and electromagnetic energy is employed, the pole pieces of the controlling magnet being insulated from each other and acting also as the electrostatic poles giving rise to a field, wherein all the tubes of force have the same general direction.

Referring to the form of device shown in Figs. 1, and 2, 14 is a highly exhausted container receptacle of any suitable impervious material, such, for example, as glass or metal. When constructed of metal, some non-magnetic, non-amalgamating substance, such, for example, as nickel-iron alloy should be employed. A cathode 15 of mercury or other suitable reconstructing vapor emitting substance, is located in the lower portion of the container 14. Two upwardly extending flanges 16 and 17 are formed in the wall of the container, and are so disposed that they are radial, throughout their length, with respect to the cathode 15. A plurality of elongated anodes 18 and 19 are mounted in these flanges so that there is a straight free arc path between each of them and the cathode 15. A plurality of electromagnets 20 and 21 are mounted to embrace the anodes 18 and 19 and are connected to a rotating commutating device connected to a main source of direct current 23. The commutating device 22 is provided with one insulating segment 24 so that as it is rotated, each of the magnets 20 is, in turn, deenergized for one-sixth of a revolution. The magnets 20 all have like poles facing outwardly so that a field similar to that employed in some types of unipolar generators is provided. The magnets 21 are excited in a similar manner (not shown). The magnets 20 and 21 may be mounted on the outside of the container as shown, or they may be mounted inside thereof, if desired. In the latter case, oxid or enamel insulated wire should be employed in order that the evacuation of the container may be carried to the proper point.

Having thus described the structure of the device of Figs. 1 and 2, the operation is as follows: Assuming an arc to be started between one of the anodes 18 and the cathode 15 in any suitable and well known manner, the magnets 20 are energized and said arc at once takes up a position between the pole pieces of the magnet 20 which is deenergized because of the insulating segment 24. As each of the magnets is deenergized in succession with the rotation of the commutating device 22, the upper end of the arc moves forward accordingly so as to always remain between the poles of the deenergized magnet and the arc, as a whole, generates, by its movement a conical surface whose apex is in the cathode 15. Therefore, the rate of rotation of the arc may be readily controlled by varying the

speed of the driving motor 22. As the arc rotates, it impinges successively upon each of the anodes 18 and causes current to flow in the primary windings 70—70 of a transformer 25 which induces current in the secondary windings 71—71 thereof, having the general characteristics and properties of three-phase alternating current which may be taken off by the mains 26. If it is desired to alter the frequency of the alternating current in the mains 26, the speed of the commutating device 22 is changed. I use the above expression "having the general characteristics and properties of three-phase alternating current" advisedly, for the reason that if relatively short anodes be employed, each phase will be energized for but one-third of the time, and each alternating current wave will have a length of 60 electrical degrees, instead of 180 degrees, as is usual. If it is desired to obtain alternating current more nearly approximating ordinary alternating current in its characteristics, the anodes 18 may be extended in length and certain of them displaced radially so that there is a general overlapping. If each of the anodes is substantially 180° in length, and each of them has the same relative location as is now the case, a current will be obtained which will be similar to ordinary three-phase alternating current, the main difference being that the shape will be extremely flat-topped instead of approximating a sine curve as is customary.

The rotating field set up by the magnets 21 may have an entirely different angular velocity from the rotating field set up by the magnets 20, and I find that no difficulty is experienced in operating two arcs within the same container, each of said arcs generating conical surfaces in its rotation and each of said arcs being entirely different in its angular velocity. In this manner, for example, both 25 cycle and 60 cycle alternating current may be obtained from the same container and from the same source of direct current. Furthermore, two separate sets of anodes may, if desired, be arranged so that one arc impinges upon both of them simultaneously and generates alternating current for two separate circuits, which circuits will have different frequencies if the number of anodes therefor are different. These actions are illustrated in Figs. 3 and 4. In Fig. 3, for example, the two groups of anodes 18—18 and 19—19 of the device of Fig. 1 are shown in skeleton view, together with the cathode 15 and the transformer 25 associated with the anodes 18—18 and a similar transformer 25' associated with the anodes 19—19. An arc 75 is shown operating upon the anodes 18—18 and is rotated at, for example, 3600 revolutions per minute by the proper control of the associated magnetic rotating means, generating 60 cycle current 130

in the transformer 25 as shown. In a like manner, an arc 76 operating on the anodes 19-19 may be rotated at a velocity of 1500 revolutions per minute, generating 25-cycle current in the transformer 25.

In the arrangement shown in Fig. 4, the two sets of anodes 18-18 and 19-19 are more closely associated with each other so that a single arc may play upon both sets. 10 If the arc be rotated at a velocity of 3600 revolutions per minute and if there be six anodes in the set 18-18 and four anodes in the set 19-19, as shown, 60-cycle current is generated in the transformer 25 associated 15 with the anodes 18-18 and 40-cycle current is generated in the transformer 25' associated with the anodes 19-19. By proper design of the container 14 and of the strength of the rotating magnetic field for 20 the specific angular velocity of the arc which is desired, a condition of equilibrium may be obtained wherein the centrifugal force of the small current-carrying particle is sufficient to maintain the arc on the anodes 18 in 25 opposition to the natural tendency of the arc to flow in a direction normal to the surface of the cathode 15.

In the form of my device shown in Figs. 5, 6 and 7 I have shown how an arc may be 30 caused to rotate so as to generate a conical surface by a suitable field having both electrostatic and electromagnetic components. An evacuated container 47 of any suitable material is provided with a plurality of 35 anodes 48 in the upper portion thereof, said anodes being arranged to lie in a circular path as clearly shown in Fig. 6. A cathode 49, of mercury or other suitable material, occupies the lower portion of the container 47. An alternating current electromagnet 50, energized from suitable mains 51, is 40 mounted within the container, and supported by suitable lugs 52. The electromagnet 50 is provided with two salient poles 53 45 which embrace the arc path. A pair of conducting plates 54 are mounted immediately in front of the pole pieces 53 and are connected, respectively, to the terminals of the secondary winding of a step-up transformer 50 55 connected to the supply means 51 through a suitable phase displacing device 56. When the mains 51 are energized, a rotating field of energy with respect to the vapor arc will be set up between the plates 54 because of 60 the fact that for a brief interval of time, for example, one of the plates 54 will be positively charged and the other will be negatively charged, causing the arc to move toward the positively charged plate because 65 of the combined action of attraction and repulsion from the two plates respectively. 90 electrical degrees later, the plates 54 will be at substantially the same potential and the electrostatic force therebetween will be substantially zero but the magnetic field be-

tween the pole pieces 53 will be at a maximum, owing to the phase displacing action of the device 56. Under the influence of the electromagnetic field a vapor arc would be forced in a given direction in a plane par- 70

allel to the plates 54. At the end of the succeeding 90 electrical degrees, the arc would be drawn toward the other plate 54 because of the reversal of polarity and at the end of the next succeeding ninety electrical degrees 75 the arc will be forced in an opposite direction in a plane parallel to the plates 54 because of the reversal of the magnetic flux. When, therefore, an arc is initiated between an anode 48 and the cathode 49 and the mains 80 51 are energized by alternating current, the arc will be caused to rotate so that its positive end engages all the anodes 48 in succession, a three phase current may be caused to be generated in the same manner as in the 85 device shown in Figs. 1 and 2.

In the form of my device shown in Figs. 8 and 9, I have shown how it is not necessary that the arc be forced to generate a conical surface in order that the same have 90 a true circular motion but the said arc may be caused to operate in substantially a single plane with very effective results. A highly exhausted container of any suitable material is provided with a plurality of anodes 57 and 95 with a cathode 58. The container is placed in a rotating magnetic field generated by a suitably wound ring 59 of magnetic material surrounding the same and energized from a suitable source of alternating current such 100 for example as the polyphase supply system 60. When an arc is initiated between one of the anodes 57 and the cathodes 58 from any suitable source 61 and the main 60 are energized, the arc will be caused to rotate so 105 that its positive ends impinge upon each of the anodes 57 in succession and a substantially plane surface is generated by the movement of the arc path. The conditions 110 affecting rotation of the arc are somewhat different than in the structure of Figs. 1 and 2. With a rotating field of the character indicated, there will always be two diametrically opposite points where the flux is zero. The arc would take up a position at either 115 one of these points. It is accordingly necessary, in order to obtain as definite a control of frequency and of phase relation as is the case with the devices of Figs. 1 and 2, to employ pairs of anodes, located 180 degrees 120 apart, in place of each of the anodes of Figs. 1 and 2. Thus to generate three-phase current, I employ twelve anodes 57, diametrically opposite ones being connected to the same current lead in each case. It will be 125 observed that, with a device of this character, after the arc has once been started into rotation, the movement thereof is substantially independent of the mass of the arc particles. The action of centrifugal force 130

does not tend to distort the arc but merely to slightly alter the velocity of the particles therein.

In the form of my device shown in Fig. 5 10, I have disclosed a method of generating a rotative field of energy similar to that shown in Figs. 5, 6 and 7, at the same time, however, dispensing with separate electrostatically charged plates. An alternating 10 current electromagnet 63 energized from mains 64 is provided with pole pieces 65 adapted to embrace the arc path. An insulating joint 66 is provided in the magnetic circuit so that the two pole pieces 65 15 are electrically separated from each other. The terminals of the secondary member of a suitable step-up transformer are connected directly to the pole pieces 65 and the transformer 67 is energized from the mains 64 20 through a phase displacing device 68. By this construction, the pole pieces 65 act alternately as electromagnetic and as electrostatic poles and in such a manner as to generate a rotating field of energy therebetween, 25 in all respects similar to that generated between the plates 54 in the device of Figs. 5, 6 and 7.

With any of the above described pieces of apparatus, I may, if desired, especially when 30 generating alternating current of high frequency, provide an arc whose current carrying particles are of relatively small mass, employing such materials, for example, as hydrogen or helium for the conducting material.

While I have in all cases shown but a single cathode, it is obvious that I may employ a plurality of cathodes distributed in a circular path and cause an arc from one anode to 40 flow thereto and to be rotated in such a manner as to generate a conical surface. Such a structure, however, would present the disadvantage that it would be necessary to separately maintain a negative electrode reluctance of each of the cathodes in a broken 45 down condition by separate maintaining means whereas with the structures that I have shown, the cathode activity is maintained. Furthermore, it would be possible 50 to construct a device wherein a plurality of anodes were arranged in a circular path and a plurality of cathodes were also arranged in a circular path and wherein the arc would be rotated in such a manner as to generate a 55 cylindrical surface. Such a structure, however, would be somewhat unstable in its operation and I deem the structure shown in the figures to be somewhat more practicable.

Where it is desired to generate alternating currents of comparatively high voltage, with attendant liability to anode short circuits, it is generally advisable to operate the inverted rectifier at a moderate voltage and to subsequently modify the output by ordinary 65 transformers, even though this occa-

sions a diminution of the efficiency, both on account of the extra apparatus and because of the greater relative effect of the constant voltage drop in the vapor arc.

As an electrostatic field must necessarily 70 be very narrow in order to have a powerful controlling action, one may, if it is desired to oscillate an arc through a considerable angle, employ a plurality of parallel-connected electrostatic fields, arranged in tandem. These may be displaced with respect 75 to each other along the arc path, if desired, so that they will exert little influence on each other.

While I have shown various modifications 80 of my invention in the appended drawing, I do not wish to be restricted thereto but I desire that only such restrictions be placed upon my invention as are set forth in the appended claims.

I claim as my invention:

1. A device for converting direct current into pulsating current comprising means producing a direct-current arc, means for causing said arc to revolve about an axis, 90 and a plurality of electrodes arranged to be engaged in succession by one end of said arc.
2. A device for converting direct current into pulsating current comprising means for producing a direct-current arc, and means for causing said arc to rotate about an axis, one end of said arc operating continuously from an electrode and the other end impinging in succession upon each of a plurality of 100 electrodes.

3. The combination with an evacuated container, of a plurality of electrodes therein, certain of said electrodes being mounted to lie in different elements of an imaginary 105 conical surface, an electrode at the apex of said conical surface, means for maintaining a direct-current arc between said last named electrode and the first named electrodes, and means for causing said arc to rotate so that 110 it always lies in said conical surface.

4. The combination with an evacuated container, of a plurality of electrodes mounted therein, certain of said electrodes being arranged substantially equidistant about the 115 perimeter of a circle, an electrode mounted substantially equidistant from all of said first named electrodes, means for maintaining a direct-current arc between said last named electrode and the first named electrodes, and means for causing said arc to rotate about an axis normal to the plane of said circle at substantially the central portion thereof, so that one end of said arc will impinge upon each of said circularly disposed electrodes in succession.

5. The combination with means producing a rotating field of energy, of a plurality of electrodes, means for producing an arc within the influence of said field of energy, and 130

the plurality of electrodes so disposed that, as the arc is rotated by the field of energy, it connects a certain one of said electrodes in succession with each of the others.

5 6. The combination with an evacuated container, of a plurality of electrodes therein, certain of said electrodes being mounted to lie in different elements of an imaginary conical surface, an electrode at the apex of 10 said conical surface, means for maintaining a direct-current arc between said last named electrode and the first named electrode, and means producing a rotating field of energy surrounding said container, whereby said 15 arc is caused to rotate so that it always lies substantially in said conical surface and impinges upon the electrodes mounted therein in succession.

7. Means for producing a rotating field of 20 energy comprising means for producing a continuously reversing electromagnetic field and means for producing a continuously reversing electrostatic field, said fields being of like frequency and disposed to act in space 25 and time-quadrature to each other upon a predetermined space.

8. Means for producing a rotating field of energy comprising means for producing a continuously varying electromagnetic field 30 and means for producing a continuously

varying electrostatic field, said fields varying at like rates and being disposed to act upon a common space with mutual time and space displacement.

9. Means for producing a rotating field of 35 force comprising means for producing a varying electromagnetic field and means for producing a varying electrostatic field, the lines of force in said two fields coinciding in direction, the magnetic field being at maximum strength when the electrostatic field is at substantially minimum strength and vice versa. 40

10. Means for producing a rotating field of force comprising means for producing a 45 continuously reversing magnetic field and means for producing a continuously reversing electrostatic field, the lines of force in said two fields coinciding in direction, the magnetic field being at maximum strength 50 when the electrostatic field is at substantially minimum strength and vice versa.

In testimony whereof, I have hereunto subscribed my name this 19th day of June, 1914.

FRIEDRICH W. MEYER.
